United States Patent Office

Des. 218,384

Patented Aug. 18, 1970

218,384

GIRL'S APRON

Kathy D. Lambert, Chicago, Ill., assignor to Marvin
Glass & Associates, Chicago, Ill., a partnership

Filed July 17, 1969, Ser. No. 18,238

Term of patent 14 years

Int. Cl. D2—01

U.S. Cl. D2—228

FIG. 1 is a perspective front view of a girl's apron, showing my new design; and

FIG. 2 is a rear plan view of the apron, reduced in scale.

I claim:

The ornamental design for a girl's apron, substantially as shown.
